UNITED STATES PATENT OFFICE.

THOMAS CORSCADEN, OF PHILADELPHIA, PENNSYLVANIA; ADELINE J. CORSCADEN ADMINISTRATRIX OF SAID THOMAS CORSCADEN, DECEASED.

DESIGN FOR A WHEEL.

SPECIFICATION forming part of Design No. 29,542, dated October 25, 1898.

Application filed March 23, 1898. Serial No. 674,946. Term of patent 14 years.

To all whom it may concern:

Be it known that I, THOMAS CORSCADEN, of the city and county of Philadelphia, State of Pennsylvania, have invented a new and original Design for Wheels, of which the following is a specification.

My improved design has reference to sheet-metal wheels, and embodies the characteristics hereinafter pointed out.

In the drawing is represented a perspective view of a sheet-metal wheel, disclosing my new and original design.

As shown in the drawing, the leading features of my design consist of an approximately flat-faced circular rim A, having the lateral edges thereof rounded or turned over, as at B B, and provided upon the under surface, intermediate of the said rounded edges B B, with an inwardly-extending annular flange C. Furthermore, the said rim has secured to it at intervals in its circumference the outer

ends of the arms or spokes E E, which are arranged in pairs and radiate from a hub at the center. The inner ends of these spokes unite in the curved parts e on the hub D. The 25 spokes E E, constituting a pair, are arranged farther apart adjacent to the tubular hub D at the center than at their connection with the annular rim. The hub D is made tubular and concentric with the rim A.

Having now described my invention, what I claim as new, and desire to secure by Letters Patent, is—

The design for a wheel herein shown and described.

In testimony of which invention I hereunto set my hand.

THOMAS CORSCADEN.
